TARGET

Arthur R. Stowell, Greenwood, Maine, assignor
to Stowell Targets, Inc., Lockes Mills, Maine

Application April 16, 1935, Serial No. 16,705

7 Claims. (Cl. 124—15)

This invention relates to apparatus particularly adapted for use in target shooting.

Where paper targets are used, it is difficult to ascertain whether or not a hit has been made without actually taking down the target for examination. Further the target shooter fails to obtain the thrill or pleasure from shooting at a paper target that he does from a target that will break upon being hit. It is usual to make targets of refractory material that will break upon being struck, but such articles made of clay or glass are expensive, and sometimes, dangerous.

The prime object of my invention is to produce a target of grained wood so manufactured and mounted that it will break upon being hit by a bullet. These targets can be manufactured sufficiently cheap to permit individuals, gun clubs, and other organizations using them.

Another object of the invention is to produce a target so constructed that it will break upon being hit and so will fall from the support on which it is mounted.

Still another object is to provide structure for mounting a series of targets so that slow, time and rapid fire can be utilized, and the scorer and shooter will immediately know the success of the shots, since the targets will be broken and dislodged from the supporting structure.

In the drawing:

Figure 1 is a front elevation showing the target disk partly inserted on the pin;

Figure 2 is a front elevation of the disk in position on the pin, as shown in Figure 3;

Figure 3 is a vertical section taken on line 3—3 of Figure 2, showing the approach of the bullet, and in dotted lines the action upon the bullet striking the disk;

Figure 4 is a vertical section of a modified form of the invention shown in Figure 3 with the disk being struck by the bullet;

Figure 5 is a front elevation of the cross grained disk before the same has been rounded off, as compared with the disk shown in Figures 1, 2, 3, and 4 made with the grain;

Figure 6 is a front elevation of a flat supporting structure, such as cardboard, to receive the targets;

Figure 7 is a fragmentary section of a modified form of pin construction;

Figure 8 is a side elevation, partly broken away, of another modified form of the pin construction; and

Figure 9 is a perspective of the preferred form of the disk being struck by a bullet.

In the drawing, in which similar parts are designed with like numerals:

Numeral 10 designates a support of cardboard or like material having a series of apertures 11 formed therein consisting preferably of three rows, five apertures to a row, as shown in Figure 6.

A pin 12, as shown in Figure 3, is formed with a base portion 13 adapted to be inserted through the aperture 11 formed in the supporting plate 10, the base portion being larger than said aperture. A shank extends from said base portion 13 and has shoulders 15 formed therein, said shoulders being of greater diameter than the base portion 13. At the opposite end of the shank 14 from the base portion 13 is formed an oval head 16 of slightly larger diameter than the shank 14.

A disk 17 cut with or across the grain has a triangular section 18 cut therefrom, the base 19 being adjacent one edge but spaced therefrom, the angular side 20 of the cut extending to the opposite periphery of the disk 17. An aperture 21, slightly smaller than the head 16 of the pin 12, is formed in the center of the disk 17 and extends through the triangular section 18, the diameter of the aperture 21 being substantially the same as the diameter of the shank 14. In the manufacture of smaller disks, the slot is often rectangular instead of triangular. However, the triangular slot may be used in all sizes as necessary.

As actually used, the pins 12 are inserted from the front of the supporting member 10, the base portions 13 being forced through the apertures 11. The material used in the supporting structure is sufficiently pliable to receive the base portions 13, even though the same are slightly larger and will closely adhere to the shank 14. The supporting structure will be flanked on one side by the base portion 13 and on the other by the shoulders 15. The disks 17 will be forced over the heads 16, as shown in Figure 1, causing the sides of the cut 18 to expand. Upon being forced clear of the heads 16, the sides will assume a normal position, as shown in Figure 2, and the aperture 21 will fit snugly around the shank 14.

Figure 6 shows the shooter forcing the disks in place. Upon the disks being positioned on the pins, the shooter is ready to start; and upon a bullet striking the disk as shown in Figure 3, the impact will force the disks against the shoulder 15, which acts as a fulcrum and causes the disk to break. This is greatly facilitated by the slot which extends substantially across the face 55

of the disk and will result in the disk being broken and falling from its support indicating to the shooter a "hit".

As shown in Figure 4, the structure is modified 5 in that instead of having the shoulders 15 formed on the shank 14, a base portion 22 is formed on the rear of the disk adapted to receive a nail or thumb tack 23 from the rear of the supporting material. Under this construction, the slot is 10 omitted, and upon the bullet striking the disk as shown in Figure 4, the same will break.

In this construction, it is preferable that the disks be cut across the grain to facilitate the breaking of the same.

15 As shown in Figure 7, the construction of the preferred form is further modified by forming the shoulders 15 separate; otherwise the construction is the same.

Figure 8 shows a modified form in which a pin 20 24, instead of having the base portion 13 as shown in the preferred form, utilizes a sharp projection 25 forming a part of the pin and extending from the shoulders 15 which can be inserted through the supporting structure 10 without the use of 25 apertures 11.

From the description given, it is apparent that I have produced a cheaply manufactured target 30 that can be quickly mounted for target shooting purposes, and which will always break upon a direct hit being scored. My construction will greatly facilitate the enjoyment of target shooting and eliminate many of the disadvantages now present. It is obvious that a frame supporting structure could be used as well as the cardboard 35 structure shown, without departing from the scope of my invention.

What I claim is:

1. A target for shooting contests or the like, comprising a wooden disk having a slot extending 40 through said disc from one periphery diametrically across the disk to a point adjacent the opposite periphery whereby said disc may be mounted.

2. A target for shooting contests or the like, comprising a wooden disk having a slot extend- 45

ing through said disc from one periphery across the disk diametrically to a point adjacent the opposite periphery and extending through the center of the disk whereby said disc may be mounted.

3. A target for shooting contests or the like, comprising a wooden disk having a triangular slot extending substantially across said target, the base of the triangle spaced from the periphery of one side of the disk, the two legs meeting in the opposite periphery. 5

4. A target for shooting contests or the like, comprising a wooden disk having a triangular slot extending substantially across said target, the base of the triangle spaced from the periphery of one side of the disk, the two legs meeting in the opposite periphery, both legs passing through 10 an aperture formed in the center of the disk. 15

5. A target for shooting contests or the like, comprising a wooden disk having a slot extending 20 from one periphery to a point adjacent the opposite periphery, and having an aperture formed intermediate the ends of the slot, a shank extending through said aperture and having a head on one end, shoulders on said shank behind said disk and a base member formed on the opposite end of said shank from said head 25 adapted to fit into a support.

6. A target apparatus comprising a supporting structure and having openings formed therein, pins in said openings, said pins having a shank portion, a disk on said shank portion, shoulders on said shank between said supporting structure and said disk, said shoulders being of greater diameter than the opening in said supporting 30 structure. 35

7. A target apparatus comprising a supporting structure, pins extending through said supporting structure, said pins having a shank portion, a disk on said shank, shoulders on said shank between said supporting structure and said disk, said shoulders being of greater diameter than that portion of the pin extending through said supporting structure. 40
